(57) **CLAIM**

The ornamental design for a gaming machine cabinet as
shown and described.

DESCRIPTION

FIG. 1 is a perspective view of a gaming machine cabinet
showing my new design;

FIG. 2 is a frontal view of the gaming machine cabinet of
FIG. 1;

FIG. 3 is a rear view of the gaming machine cabinet of FIG.
1;

FIG. 4 is a side view of the gaming machine cabinet of FIG.
1;

FIG. 5 is an opposite side view of the gaming machine
cabinet of FIG. 1;

FIG. 6 is a top view of the gaming machine cabinet of FIG.
1; and,

(Continued)

FIG. 7 is a bottom view of the gaming machine cabinet of FIG. 1.

The broken lines shown in the drawings illustrate portions of the gaming machine cabinet that form no part of the claimed design.

1 Claim, 6 Drawing Sheets
